US00D893524S

(12) **United States Design Patent** (10) Patent No.: **US D893,524 S**
 (45) Date of Patent: **** Aug. 18, 2020**

(54) **DISPLAY SCREEN WITH GRAPHICAL USER INTERFACE**

(71) Applicant: **DoseMe Pty Ltd**, Taringa Queensland (AU)

(72) Inventor: **Paul Sabourenkov**, Taringa (AU)

(73) Assignee: **DoseMe Pty Ltd**, Taringa Queensland (AU)

(**) Term: **15 Years**

(21) Appl. No.: **29/643,059**

(22) Filed: **Apr. 4, 2018**

(51) LOC (12) Cl. **14-04**

(52) U.S. Cl.

USPC **D14/486**

(58) **Field of Classification Search**

USPC **D14/485-495**

(57) **CLAIM**

The ornamental design for the display screen with graphical user interface, as shown and described.

DESCRIPTION

The FIGURE is a front view of a display screen with a graphical user interface, or a portion thereof, showing my new design.

The broken line showing of a graphical user interface is included for the purpose of illustrating portions of the article and forms no part of the claimed design.

1 Claim, 1 Drawing Sheet

Choice of Dose Calculation

Individualised Target	Guideline Dose	Label Dose
35mg (historical) for 4 days only	30mg Twice daily for 3 doses	30mg Twice daily for 3 doses
Target AUC ₀₋₈ : 4600 ug.h/L Predicted AUC ₀₋₈ : 4628.4 ug.h/L	Peak 939.1 ug/L Trough 1.4 ug/L AUC ₀₋₈ 4342.1 ug.h/L	Peak 749.3 ug/L Trough 0.9 ug/L AUC ₀₋₈ 4452.8 ug.h/L
Peak 943.9 ug/L Trough 0.9 ug/L AUC ₀₋₈ 4628.4 ug.h/L	Historical Report Dose date in past	Historical Report Dose date in past
Historical Report Dose date in past	Weight Warning Dose is less than 10mg/kg	Weight Warning Dose is less than 10mg/kg
Selected	Select	Select
